UNITED STATES PATENT OFFICE

EDMUND C. MORGAN, OF NEW YORK, N. Y.; OLIVE EUGENIE MORGAN EXECUTRIX OF
SAID EDMUND C. MORGAN, DECEASED

MINING AND LOADING APPARATUS

Application filed December 23, 1919, Serial No. 346,903. Renewed August 26, 1929.

My invention relates to mining and loading machines and one of the objects of my invention is the provision of improved and efficient apparatus of this type.

More particularly it is the object of the present invention to provide splitting tools and mechanism for operating the same to dislodge coal from an arcuate mine wall in position to be automatically received by loading apparatus and transferred automatically to a mine car on a track in the mine chamber back of the mining and loading apparatus.

Another object of the present invention is the provision of kerf cutting mechanism particularly adapted to the cutting of arcuate kerfs in a mine wall to facilitate the dislodgment by means of coal splitting mechanism associated with such kerf cutting mechanism in a mining machine.

Other objects of the invention will appear hereinafter, the novel combinations and features being set forth in the appended claims.

Referring to the accompanying drawings Fig. 1 is a plan view of my combined mining and loading machine;

Fig. 2 is an elevational view of the combined mining and loading machine with a portion of the kerf cutting mechanism included to show its relation to the other parts;

Fig. 3 is an enlarged elevational view, partly in section, of the coal splitting mechanism shown at the right hand portion of Fig. 2;

Fig. 4 is an enlarged elevational view, partly in section, of the right hand portion of Fig. 2, but looking from left toward the right.

Fig. 5 is a sectional detail view of the three-way valves particularly adapted for use in the control system of pressure pipes shown in Figs. 1 and 2;

Fig. 6 is a sectional elevation of the forward swinging conveyer and of the mechanism for delivering coal to said conveyers;

Fig. 7 is a plan view of the structure shown in Fig. 6;

Figs. 8 and 9 are elevational views of the coal splitting mechanism shown in Figs. 1, 2, 3 and 4 and comprises chisel cutting edges;

Figs. 10 and 11 illustrate modified coal splitting tools comprising pointed elements;

Fig. 12 is a plan view, partly in section, of

the kerf cutting mechanism the position of which when not in use being shown by the dotted lines at the upper right hand portion of Fig. 1;

Fig. 13 is a sectional elevational view taken on a line 13—13 of Fig. 12 looking in the direction of the arrows;

Fig. 14 is a sectional detail view taken on the line 14—14 of Fig. 12 looking in the direction of the arrows;

Fig. 15 is a diagrammatic view illustrating the operation of the coal splitting tools of Figs. 1 to 4 inclusive when the wall tools are in vertical alinement;

Fig. 16 illustrates diagrammatically the operation of splitting out a body of material intermediate the floor and roof;

Fig. 17 is a plan view of portions of the splitting tools when adjusted so as to have an intermediate tool in advance of other tools spaced above and below such intermediate tool;

Fig. 18 is similar to Fig. 16 but shows the operation of dislodging the coal after the middle section has been split out of space on to the mine floor;

Fig. 19, Fig. 20 and Fig. 21 are views respectively similar to Figs. 15, 16 and 18 but illustrate diagrammatically the use of the pointed coal splitting tools illustrated in Figs. 10 and 11;

Fig. 22 is a plan view of the pointed tools used for securing the operations illustrated in Figs. 19, 20 and 21, the intermediate tool being ahead of those above and below to secure the preliminary dislodgment of a central section thereby facilitating dislodgment of the other sections as illustrated in Fig. 21.

Figs. 23 and 24 illustrate diagrammatically the use of coal splitting mechanism to dislodge blocks of material previously separated by kerfs;

Fig. 25 is a plan view of modified mechanism for swinging the coal splitting mechanism with sufficient force to operate the latter, such swinging mechanism being capable of returning the parts including the receiving conveyor to initial position and therefore serving as a substitute for the one-way swinging mechanism of Figs. 1 and 2 and of the

walking fluid pressure jack mechanism of Figs. 1 and 2;

Fig. 26 is an elevational view of the structure shown in Fig. 25 and shows a plurality of ropes for moving the coal splitting tools in dislodging direction and a single rope for returning the coal splitting tools to initial position; and

Fig. 27 is a diagrammatic illustration illustrating the advantages of the use of coal splitting devices for dislodging material having therein small sections of a very hard material which can be cut, if at all, by means of coal cutting mechanism only with very great difficulty.

Referring to Figs. 1 and 2 it will be seen that the main frame 28 is mounted on tractor mechanism comprising endless tractor belts 29 and 30 for transporting the mining and loading machine over the mine floor 31 in advance of the track 32. I prefer to use tractor mechanism operatively connected to the motor 33 so as to distribute the weight of the mining and loading machine over a wider area not only to facilitate transportation of the mining and loading machine over the mine floor but also to assist the roof jacks 34 and 35 in more firmly holding the main frame 28 in adjusted position during the mining and loading operations hereinafter described. These roof jacks are preferably pivotally connected to the upper side portions of the frame 28 as shown in Figs. 1 and 2, the pivotal connection being shown at 36 in Fig. 2. A wheel 37 screw threaded on the rod 38 may be relied upon to thrust the upper end of said rod against the roof 39.

At the lower portion of the frame 28 is a rearward extension 40 to which is pivoted at 41 the lower side of the hopper 42. This hopper is provided with a rearward extension 43. An endless conveyor 44 is mounted to extend from the bottom of the hopper 42 to the outer open end 45 of the horizontal chute 43. This conveyor 44 may be operated by means of the motor 46.

Connected to the upper rear portion of the frame 28 is a horizontal U-shaped extension 47 at the center of which as indicated at 48 in Figs. 1 and 2 is pivoted the arm 49 which is T-shaped and connected at 50, 50 to the hopper 42 and chute 43. It will thus be seen that the pivotal connections 41 and 48 are in vertical alinement and permit the hopper 42 the chute 43 and the conveyor 44 to be swung laterally so that the delivery end 45 of the conveyor 44 may extend into a mine car 51 on the track 32 or on a track parallel thereto on either side of the track 32.

Mounted on the frame 28 is an endless belt conveyor 52 in position to receive material delivered into the hopper 53 and transfer such material rearwardly and upwardly for delivery into the hopper 42. It should be

noted that the hopper 42 is comparatively large and deep so that it may act temporarily as a storage hopper while the conveyor 52 continues to deliver material to such hopper and the conveyor 44 is out of operation during the removal of a loaded mine car and the bringing up of an empty mine car.

Mounted on the forward end of the frame 28 is a supplemental frame 54 provided with a ring 55 surrounding the lower portion of the hopper 53 and having an annular bearing connection with the frame 28 so as to support the supplemental frame 54 for swinging movements laterally on an upright axis approximately at the center of the hopper 53.

Mounted on the frame 54 and extending radially relative to the upright axis 56 of swinging movement of the frame 54 is a receiving endless conveyor operated by a motor 58. At one side of the frame and the conveyor 57 is connected a scooping plate 59 for directing on to the conveyor 57 such material as may be on the floor ahead of it. It should be noted that the conveyor 57 swings with the supplemental frame 54 on the axis 56 and is therefore in delivery communication with the hopper 53 through a range of approximately 180 degrees.

On the frame 54 back of the receiving conveyor 57 are mounted a plurality of coal splitting tools such as those shown in Figs. 8 and 9. By referring to Fig. 3 it will be seen that tool holders 60 and 61 are provided respectively adjacent to floor and roof of the mine chamber. The tool holder 60 carries the spaced apart splitting tools 62 and 63 which also have a cutting action on account of being in the nature of chisels. The tool holder 61 carries similar coal splitting and cutting tools 64 and 65. The upper side of the tool holder 61 carries a coal splitting and cutting tool 66 and the lower tool holder 60 carries a similar splitting and cutting tool 67 as shown in Figs. 3 and 4. The tools, 62, 63, 64 and 65 may be in vertical alinement or the intermediate tools 65 and 62 may be in advance of the upper-most and lower-most tools 64 and 63. The tools 62, 63, 64 and 65 are rigidly connected to the tool holders 60 and 61 as by means of set screws as illustrated at 68 in Figs. 1, 8 and 9. It will thus be seen that the tools 62, 63, 64 and 65 constitute spaced-apart fingers in approximate vertical alinement movable with the frame 54 along arcuate paths of travel on the upright axis 56 to tear asunder or dislodge the coal as illustrated in Fig. 1 and also in Fig. 15. The fingers 62 and 63 are rigidly connected to the frame 54 and move bodily therewith when the latter is swung on the upright axis 56.

The tool holder 61 is connected to an auxiliary frame 69 to which are rigidly connected the downwardly extending piston rods 70, 71 extending through the bearing boxes 72 and

73 to the pistons 74 and 75 in the vertical cylinders 76 and 77 in the frame 54. By means of this mechanism the fingers 64 and 65 may be adjusted in elevation together with the finger 66 and at the same time the tool holder 61 may be rigidly connected to the frame 54 so as to move bodily therewith, particularly when the pistons 74 and 75 together with the piston rods 70 and 71 are located a comparatively wide distance apart.

10 Inasmuch as the frame 54 is so mounted on the frame 28 as to always occupy a position spaced a short distance from the mine floor the fingers 62 and 63 will always remain approximately at their adjusted elevations. It should be understood, however, that the finger 62 may have any desired spacing and may initially be located at varying elevations. In low roof mine chambers the tool holder 61 together with the parts connected thereto including the piston rods 70 and 71 may be entirely omitted and the fingers on the frame 54 relied upon to dislodge the material particularly when the upper finger 62 is located 20 at an elevation approximately that of the chute 43.

Furthermore, the fingers 62 and 63 shown in Fig. 3 may be slightly adjusted in elevation by the floor jack 78 which comprises a piston 30 79 movable in the cylinder 80 to force the plunger 81 against the floor 31. A similar roof jack is shown at 82 on the tool holder 61 for thrusting the plunger 83 against the roof 84. The primary function of the jacks 35 78 and 82, however, is to guide the tool holders 60 and 61 respectively along the floor and roof of the mine chamber so as to hold the dislodging tools 62, 63 and 64, 65 at predetermined distances from the floor and roof.

40 By referring to Fig. 4 it will be seen that the roof cutter 66 is pivoted at 85 to the tool holder 61 and that the floor cutter 67 is likewise pivoted at 86 to the tool holder 60. The roof cutter 66 may be adjusted in position by means of the fluid pressure motor 87 comprising the cylinder 88 and piston 89 connected by the piston rod 90 at 91 to the lever 92 connected to the cutter 66. The floor cutter 67 is likewise adjusted in position by means of the lever 93 pivotally connected at 94 to the piston rod 95 which is connected to the piston 96 in the cylinder 97 of the fluid pressure motor 98.

In order to exert considerable pressure back of the tool holders 60 and 61 I have provided a pair of walking roof jacks 99 and 100. The roof jack 99 comprises a cylinder 101 for receiving the plunger 102 at the upper end of which is a roof plate 103 having a serrated upper surface. Likewise the roof jack 100 comprises a cylinder 104 for receiving the plunger 105 at the upper end of which is the roof plate 106.

At the lower portions of the cylinders 101 and 104 are annular bearings 107 and 108 for

receiving the rings or collars 109 and 110 which are respectively connected to the piston rods 111 and 112. The latter are connected respectively to pistons 113 and 114 in the cylinders 115, 116, pivotally connected as indicated at 117 in Fig. 4 to the tool holder 60, horizontal slots 117 and 118 being provided in the tool holder 60 to permit lateral swinging movements of the fluid pressure motors comprising the cylinders 115, 116 when such fluid pressure motors are operated to move the dislodging tools 62 and 63 into the unmined mass.

Surrounding the plungers 102 and 105 so that the latter will be freely slideable therethrough are the rings or collars 119 and 120 which are connected respectively by the piston rods 121 and 122 to the pistons 123 and 124 in the cylinders 125 and 126. The latter are pivotally connected to the tool holder 61 as indicated at 127 in Fig. 4, and slots 128 and 129 are provided in the tool holder 61 to permit lateral swinging movements of the fluid pressure motors comprising the cylinders 125 and 126 when such fluid pressure motors are operated to actuate the dislodging tools 64 and 65.

It should be understood that the horizontal fluid pressure motors shown in Figs. 3 and 4 are also relied upon to alternately move the roof jacks 99 and 100 forwardly to new roof propping positions where such roof jacks will alternately act as anchorages for the fluid pressure motors when acting to thrust forward the dislodging tools, particularly those designated 62, 63, 64 and 65. Each of the fluid pressure motors shown in Figs. 3 and 4 may be controlled by a set of manually operated valves each having the construction illustrated in Fig. 5. 105

For instance when the handle 130 is in its right hand position as shown in Figs. 3 and 4 the valve passage 131 of the valve 132 will connect the chamber 133 through the pipe 134 and the pipe 135 to the supply pipe 136. The 110 passage to the exhaust pipe 137 will therefore be closed and pressure will be exerted on the piston 123 to move the same to the left as viewed in Fig. 4. At the same time as the lever 130 moves to the right the lever 138 115 should be moved to the right to connect the supply pipe 139 through the valve 140 to the chamber 141 to effect movement of the piston 113 to the left. When the piston 123 is moved to the left the valve 141 will also occupy a 120 position similar to that shown in Fig. 5, 142 designating the exhaust pipe now corresponding to the pipe 135 in Fig. 5. In the same manner when the lever 138 is moved to the right the valve 143 opens the space to the 125 left to the piston 113 through the exhaust 144.

By referring to Fig. 2 it will be seen that the supply pipe 136 is connected to a manifold 145 and a valve 146 is provided in the pipe 136 to control the flow of the pressure medium.

to the fluid pressure motor comprising the cylinder 125. In a similar manner the pipe 139 is connected to the manifold 145 and provided with a controlling valve 147.

The cylinder 101 of the roof jack 99 is connected by a pipe 148 to the manifold 145 and this pipe is provided with a controlling valve 149 similar to that shown in Fig. 5 an exhaust connection being indicated at 150. Therefore, when the valve 149 is opened the pressure medium going through the pipe 148 into the cylinder 101 will force the plunger 102 into roof engaging position to anchor the roof jack 99. When the valve 149 is opened to the exhaust 150 the plunger 102 will slide through the ring or collar 119 and thus release the plate 103 from the roof. When the roof jack 99 is in released position and the pistons 113 and 123 are moved to the left the said roof jack 99 is moved forward to a new position whereupon the valve 149 is again manipulated to move the plunger 102 to anchoring position. Immediately after the roof jack 99 has been thus moved forward and again anchored the roof jack 100 is released by opening the valve 151 to exhaust 152 so that the pressure in the cylinder 104 will be relieved and permit the plunger 105 to descend. As soon as this occurs the levers 130 and 138 are moved toward the left as viewed in Fig. 4 so as to connect the chambers 133 and 154 to the exhausts 137 and 153 and so as to connect the supply pipes 136 and 139 to the chambers at the left of the pistons 123 and 113. Since the roof jack 99 is anchored at this time the tool holding frames 61 and 60 will be moved forward to cause the fingers or diggers 62, 63, 64 and 65 to dig into the material at the upright arcuate mine wall and dislodge the material as indicated in Fig. 1 in position to be received by the conveyor 57 for transfer to the hopper 53 and in turn to be transferred by the conveyor 52 to the hopper 42 for transfer by the conveyor 44 to the mine car 51.

While the roof jack 99 is in anchored position and the fluid pressure motors connected thereto are operating to move the tool holders 60 and 61 forward arcuately the roof jack 100 should be moved forward to a new position by means of the fluid pressure motors connected thereto which fluid pressure motors comprise the cylinders 126 and 116 as shown in Fig. 3. These fluid pressure motors are connected by the pipes 155 and 156 to the manifold 145, the pipe 155 being provided with a valve 157 and the pipe 156 being provided with a valve 158. The pistons in these fluid pressure motors may be moved in one direction or the other by operating the levers 159 and 160 which correspond to the levers 130 and 138 and are connected to similar sets of valves each of which has a construction illustrated in Fig. 5. The throw of each of these levers is approximately 90 degrees as

illustrated by the dotted line position 161 in Fig. 5.

Inasmuch as the fluid pressure motors 78, 82, 87 and 98 also have reciprocating pistons the movements of the latter may be controlled by sets of valves similar to those operated by lever 130. To operate the motor 87 the lever 162 is moved in one direction or the other to control the pressures on the piston 89 from the supply pipe 163 which is connected to the manifold 145. A supply pipe 164 extends from the manifold to the valves operated by the lever 165 to control the motor 98. The lever 166 controls the motor 78 by controlling the flow of fluid pressure from the pipe 167 which is also connected to the manifold 145. The lever 168 controls the motor 82 by controlling the pressure from the pipe 169 which may also be connected to the manifold 145. Each of the pipes connected to the manifold may be provided with a single manual valve, those in the pipes connected to the anchoring roof jacks being provided with exhausts as indicated at 150 and 152.

The manifold 145 is connected by a pipe 170 through a swivel joint 171 to the pipe 172 which is connected to the pump 173 connected to the motor 33. The swivel joint 171 is located at the axis 56 as shown in Fig. 1 so that the manifold 145 and all the pipes connected thereto may be moved bodily along arcuate lines while the pump 173 is being operated by the motor 33 to maintain fluid pressure in the manifold 145 to operate the fluid pressure motors whenever desired.

It should be noted that when the fluid pressure motors connected to the roof anchoring jacks are operated to move the series of diggers arcuately along the mine wall on the upright axis 56, such fluid pressure motors will be moved arcuately on the axis of the anchored roof jacks but the collars 119, 120 and 109, 110 will permit such movements of the fluid pressure motors relatively to the roof jacks, and such arcuate movements relatively to the tool holders 60 and 61 will be permitted by reason of the pivotal connections indicated at 117 and 127 in Fig. 4, sufficient lateral movement of the fluid pressure motors relatively to the tool holders 60 and 61 being permitted by the horizontal slots 174, 118 and 128, 129.

It should also be noted that while the strokes of the pistons relatively to the cylinders of the fluid pressure motors connected to the roof jacks are continuous from one end of each cylinder to the other end thereof during the normal operation of the walking roof jacks it is desirable to lock the pistons in the motors 87, 98, 82 and 78 in adjusted position and this may be effected by movements of the levers 162, 165, 168 and 166 to vertical positions where the passage 131 shown in Fig. 5 will be cut off from any of the pipes to which the valves are connected.

However, if the pistons are at the ends of the cylinders such locking may be effected by closing the valve adjacent the manifold 145.

As shown in Fig. 6 the receiving conveyor 57 may comprise an endless belt 175 mounted 5 on rollers 176 and 177 and provided with lateral sprocket chains 178 and 179 for engagement by the sprockets 180 and 181 on the transverse shaft 182 connected to the gearing 183 operated by the motor 58. Preferably 10 the endless belt 175 travels upwardly along a chute comprising the vertical side plates 185 and 186 and the bottom plate 187.

The conveyor frame is pivoted at 188 on 15 a horizontal axis on the upper peripheral edge of the hopper 53 so that this receiving conveyor 57 may be moved up and down on the axis 188 independently of the frame 54. The outer end of the conveyor may rest on 20 the floor and slide over the same or the vertical plate 189 connected to the bottom of the conveyor frame at one side thereof may be relied upon to rest against the ring 55 as shown in Fig. 6 to hold the conveyor spaced 25 slightly from the floor at the mine wall.

Extending across the front end of the conveyor is a scoop 190 provided with a plurality of spaced-apart slots 191 to receive the teeth 192 of the jigger plate 193 which is located at the floor at the base of the mine wall in position to move the dislodged material on to the conveyor belt 187 as shown in Fig. 6. The horizontal floor plate 193 extends under the scoop 190 and is provided 30 with a rearward extending arm 194 mounted on the bracket 195. A spring 196 is connected between the vertical plate 189 and the forward end of the arm 194 to continually urge the plate 193 forward to a position beyond the 35 arcuate face of the mine wall. The conveyor is located ahead of the dislodging mechanism as shown in Fig. 1 but when the plate 193 engages unmined material its forward movement will be stopped but when the material 40 is dislodged the plate will move under such dislodged material as shown in Fig. 6. However, the plate 193 may have the length of 45 its extended portion varied so as to assure the movement of the dislodged material on to the conveyor 57.

In order to secure a comparatively slow movement of the plate 193 with the material thereon toward the conveyor I have provided 50 an upwardly extending lever 197 at the rear end of the arm 194 in position to be engaged by the pin 198 extending laterally from the gear 199 as shown in Figs. 6 and 7. This gear is operatively connected by the pinion 200 to the motor 201 which is mounted on 55 the vertical plate 189. When the pin 198 is rotated it engages the lever 197 to move the arm 194 and the plate 193 rearwardly against the action of the spring 196. The teeth 192 engaging the dislodged material will effect 60 movement of the latter slowly toward the 65

left as viewed in Fig. 6. After the pin 198 has been rotated clock-wise as viewed in Fig. 6 slightly more than 180 degrees the arm 194 will be released and the spring 196 will be free to act to suddenly move the plate 193 forward under any material at the base of the mine wall in the path of the plate. 70

In Fig. 15 I have illustrated diagrammatically the relative positions of the diggers or splitting tools 62 to 67 inclusive and the manner in which these tools act to split the material not only along the upright mine wall but also from the roof and floor, the roof and floor tools being respectively indicated at 66 and 67. 75

In Figs. 16, 17 and 18 I have illustrated diagrammatically the operation of the diggers or splitting tools when an intermediate tool 62^b is located in advance of the upper and lower tools 64^a and 63^a when viewed in plan shown in Fig. 17. In this operation the intermediate section *b* is first dislodged thereby facilitating the operation of the remaining tools in splitting away the sections represented in Fig. 18 toward the space *d* from 80 which the first section *b* has been removed. In other words, by the preliminary removal of the section *b* from the space *d* the splitting of the remaining sections *a'*, *c'*, *d* and *e* is 85 facilitated on account of the open space afforded at *d*. 90

Fig. 19 illustrates the operation when such pointed diggers as those shown in Figs. 10 and 11 are used in vertical alinement. The pointed tools 202, 203 and 204 may be placed 100 in vertical alinement as shown in Fig. 19 but in some instances it may be preferred to have the intermediate pointed tool in advance of the others as illustrated in Figs. 20, 21 and 22. The intermediate section *g* may then first be 105 dislodged from the space *h* thereby facilitating the dislodgment of the upper and lower blocks *i* and *j*. The pointed tool 203^a may be relied upon to dislodge the block *g* because in advance of the upper and lower tools 202 110 and 204. 115

In Fig. 23 I have illustrated the method of dislodging blocks of coal above and below spaced-apart kerfs 205 and 206 which have been cut horizontally in a mine wall prior to the use of the spaced-apart digging coal splitters 207 and 208, the spaced-apart floor coal splitters 209 and 210 and the vertical coal splitter 211 located approximately midway between the floor and roof of the mine 120 chamber. 125

In Fig. 24 I have illustrated the method of first cutting or removing a comparatively large section from the intermediate space 212 and then splitting the coal from the roof by means of the spaced-apart dislodging devices 213 and 214, and splitting the coal from the floor by means of the spaced-apart dislodging devices 215 and 216. 130

In Fig. 27 I have illustrated the advantage 135

of using spaced-apart diggers to dislodge the coal instead of cutting it out. This is particularly true with respect to the pointed digger 217 shown in Figs. 10 and 11. It sometimes happens in the mining of coal that very hard substances such as iron pyrites are encountered by cutting apparatus and such hard substances are so difficult of being cut that the cutting tools will be dulled very quickly or even broken and in some instances it is impossible for the cutting mechanism to cut through such hard substances at all. By means of the diggers herein illustrated when such hard substances are encountered as illustrated at 218 in Fig. 27 the force exerted on the digging tool, while not sufficient to break the hard substances imbedded in the coal, will be sufficient to break away a comparatively large section of coal as indicated at 219 in Fig. 27 thus removing the coal together with the hard substances imbedded therein without interfering with the continued operation of the mining machine embodying such digging or coal splitting tool.

After a complete semi-circular stroke of the dislodging mechanism has been made from the position of dotted lines shown in Fig. 1 such dislodging mechanism may be quickly returned to initial position in readiness for another series of dislodging operations, after the tractor mechanism has been operated to move the entire mining and loading machine to a new forward position. To effect this quick return movement a draft rope 220 is connected to the frame 54 as shown in Fig. 2 and wound on the drum 221 connected for operation to the motor 222.

When the material to be dislodged is comparatively soft so that fluid pressure motors such as hydraulic motors are not necessary to secure the requisite amount of force to operate the diggers to dislodge the material from the mine wall the rope winding mechanism illustrated in Figs. 25 and 26 may be used to swing the diggers arcuately to cause them to dislodge the material. In this event the walking roof jacks together with the other fluid pressure mechanism may be omitted and the roof jacks 34 and 35 relied upon to hold the main frame 28 in stationary position during the operation of the dislodging mechanism. The rope-winding mechanism illustrated in Figs. 25 and 26 includes the rope-winding drum 221 the motor 222 and the single rope 220 as shown in Figs. 2 and 26, for returning the dislodging mechanism to initial position, but the connections to secure dislodging operation of the diggers includes the plurality of ropes 23 connected to the side of the ring 55 opposite the point 224 to which the rope 220 is connected. By means of suitable reduction gearing between the motor 222 and the winding-drum 221 a slow but very powerful turning movement may be exerted on the ring 55 to move the frame 54 to-

gether with the digging tools mounted thereon arcuately along the mine wall to effect dislodgment of the material as illustrated in Fig. 1. When the fluid pressure apparatus is omitted and the rope-winding mechanism used for moving the diggers in dislodging direction the upper tools 64 and 65 shown in Fig. 3 are rigidly connected through the structure shown in this view to the frame 54 so as to move bodily with the latter.

In order to cut the kerfs illustrated at 205 in Fig. 23 a kerf cutter may be mounted on the main frame 28 as shown in Fig. 2. Such a kerf cutter is illustrated in Figs. 12, 13 and 14 and when out of operation may occupy 80 the dotted line position shown in Fig. 1. This kerf cutting mechanism is so mounted on the frame 28 as to be detachable therefrom. The frame 225 of the kerf cutting mechanism constitutes an annular ring which 85 is trunnioned at 226, 227 to the forwardly extending spaced-apart arms 228, 229 and the latter are pivotally connected as illustrated at 230, 231 to the upper ends of rack bars 232, 233 extending vertically along the 90 guide ways 234 and 235 at the sides of the frame 28.

In Fig. 2 I have diagrammatically illustrated mechanism for lifting and lowering the vertical rack bars to adjust the elevation 95 of the spaced-apart horizontal beams 228 and 229 to adjust the elevation of the kerf cutting mechanism. This mechanism for lifting and lowering the vertical rack bars comprises a motor 236 connected by a shaft 237 100 to gearing meshing with such rack bars. A shaft 238 as shown in Fig. 1 extends transversely across the upper portion of the frame 28 a sufficient distance above the conveyor 52 and a sufficient distance to the right of the 105 delivery end thereof to not interfere with the passage of material being transferred from the hopper 53 to the hopper 42. On the opposite side of frame 28 a longitudinal shaft 239 parallel to the shaft 237 transmits power 110 from the transverse shaft 238 to the gearing for operating the vertical racks corresponding to those designated 232 and 233 on the opposite side of the machine. The starting and stopping and reversal of the electric 115 motor 236 is all that is necessary to regulate the elevation of the parallel bars 228, 229 and the kerf cutting machine mounted thereon.

By referring to Fig. 12 it will be seen that 120 the ring 225 incloses an inner ring 240 which is trunnioned at 241 and 242 on axes at right angles to the axes of the trunnions 226, 227. Rotatably mounted within the ring 240 is a circular frame 243, the ring 240 having an 125 annular bearing therefor. Depending from the disc 243 is an auxiliary frame 244 for carrying two electric motors 245 and 246. The motor 245 is connected by the worm gear 247 to the pinion 248 which meshes with 130

the annular gear 249 at the lower portion of the ring 240.

Extending forwardly from the auxiliary frame 244 is a tubular frame 250 which carries at its outer end the gear box 251 for inclosing the sprocket wheel 252 in a closed chamber 253 which may be filled with lubricating material. The sprocket wheel 252 is mounted on the shaft 254 which extends along the tubular frame 250 to the gear 255 which meshes with the pinion 256 on the shaft of the motor 246.

Mounted on the gear box 251 is a flat disc 257 having a ball race at its periphery for connection by the circular series of balls 258 to the cutter ring 259 carrying the cutters 260. Secured to the outer edges of the disc 257 are spaced-apart annular plates 261 and 262 in the planes of the opposite surfaces of the disc 257. These annular rings are of sufficient width to completely cover the ring 259 and the sprocket gear notches 263 therein thereby preventing any dust or dirt from reaching the ballbearings. The lubricating material within the chamber 253 will however be thrown by centrifugal force from the sprocket gear 252 to the ballbearings through a slight space between the ring 259 and one of the plates 261 or 262.

After the kerf cutter shown in Figs. 12 and 13 has been adjusted in elevation by operating the motor 236 shown in Fig. 2, such kerf cutter may also be adjusted in inclination either on the axis of the trunnions 226, 227, to incline the kerf cutter up or down toward the mine wall longitudinally in advance of the mining and loading machine, or on the axis of the trunnions 241, 242 to incline the kerf cutter up or down in the direction in which the dislodging mechanism is moved. By turning the wheel 264 mounted on the bracket 265 the whole kerf cutting machine may be tilted on the axis of the trunnions 226, 227. By turning the wheel 266 the ring 240 together with the kerf cutting mechanism mounted thereon may be tilted on the axis of the trunnion 241, 242. It should be noted that the wheel 266 is free to turn in the bracket 267 which is connected to the ring 240. The wheel 266 is provided with a screw threaded rod 268 which is screw threaded through the bracket 269 on the ring 225 a short distance from the trunnion 241. The looseness of the turning connection at 270 may be relied upon to permit relative tilting movements between the ring 240 and the ring 225.

The wheel 264 is mounted loosely for turning movements in the bracket 265 which is attached to the arm 229. A screw-threaded rod 271 extends upwardly from the wheel 264 and is screw-threaded through the bracket 272 which is attached to the outer ring 225. The looseness of the connection between the rod 271 and the bracket 265 may be relied upon

to permit of the desired tilting of the entire kerf cutter on the axis of the trunnions 226, 227.

In order to operate the kerf cutter the electric motor 246 is driven in the proper direction to secure rotation of the cutter ring 259 in a clock-wise direction as viewed in Fig. 12, and the electric motor 245 is operated in the proper direction to secure swinging movement of the kerf cutter on an upright axis at the center of the disc 243. The kerf cutter is so mounted on the machine that it may cut a kerf in advance of the dislodging mechanism and such a kerf may be cut independently of the operation of the dislodging mechanism, either before the latter begins to operate or during the operation thereof. It will also be seen that by reason of the independent operation of the kerf cutting mechanism a plurality of kerfs may be cut at various elevations before the dislodging mechanism is operated to dislodge material adjacent said kerfs.

It should be particularly noted that the plane of the kerf cutter is at all times substantially at right angles to the upright axis of arcuate swinging movement of the frames 244 and 250. It is therefore obvious that irrespective of the adjustment of the kerf cutter, whether to one side or to the other or whether up or down the kerf cut will always be in a plane and such kerf will be of substantially the same thickness throughout, there being no tendency to cut a conical kerf on account of the adjustment of the inclinations of the kerf cutter. It will also be seen by referring to Figs. 1 and 2 that the center of the disc 243 is approximately in vertical alignment with the axis 56 so that the inner ends of the kerfs will be approximately in vertical alignment with the paths of travel of the coal splitting tools. But the axis on which the kerf cutter is swung will always be shifted to one side or the other or forwardly or backwardly in accordance with the adjustments on the various trunnions shown in Fig. 12 because the kerf cutter shown in Figs. 12 and 13 is a self contained mining machine wherein the plane of the kerf cutter always remains at right angles to the axis extending through the disc 243 at the center thereof and at right angles thereto.

In the co-pending application Serial No. 226,690, filed October 17, 1927, for kerf-cutters for mining apparatus, as a division of the present application, there is described and claimed the universal mounting of the kerf-cutter and the adjusting mechanism for such universal mounting, combined with means for operating the kerf-cutter.

In the co-pending application Serial No. 775,173, filed June 23, 1918, for mining machine, and in the division thereof bearing Serial No. 306,309, filed September 17, 1928, for method of and apparatus for mining coal,

there is broadly claimed the universally adjustable support for a self-contained kerf-cutting machine, combined with mechanism for operating the kerf-cutting mechanism including swinging feeding movement thereof on an axis permanently at right angles to the plane extending through the plane of the kerf cut by said kerf-cutting mechanism, all combined with mechanism for adjusting the universal support and the position of the kerf-cutting mechanism.

Obviously those skilled in the art may make various changes in the details and arrangement of parts without departing from the spirit and scope of my invention as defined by the claims hereto appended, and I wish therefore not to be restricted to the precise construction herein disclosed.

Having thus fully described my invention 20 what I desire to have protected by Letters Patent of the United States is:

1. In a mining and loading machine, digging mechanism, framework for supporting said digging mechanism for arcuate movement along an upright mine wall, hydraulic means for pushing said digging mechanism to dislodge material from such upright mine wall, and loading apparatus for automatically receiving the dislodged material and transferring such dislodged material to loading position.

2. In a mining machine, the combination with a supporting frame, of a plurality of spaced-apart penetrating splitting tools each having an upright knife edge and wedging surfaces receding therefrom and mounted on said frame in an upright series extending from the floor to the roof of the mine chamber and each mounted on said frame in a stationary position relative to said frame, means for operating said tools by moving the same arcuately as a unit relatively to said supporting frame to cause said tools to penetrate the solid face of the mine vein and dislodge the mineral 45 therefrom in large pieces over a wide area extending from the floor to the roof of the mine chamber.

3. In a mining machine, the combination with a supporting frame, of a supplemental frame mounted thereon for movement relatively thereto, an upright series of spaced-apart coal splitting tools mounted on said supplemental frame and movable bodily therewith, and fluid-pressure mechanism for exerting powerful pressure horizontally on said supplemental frame to move the same arcuately and horizontally relatively to said main frame and push the said coal splitting tools into the solid face of the coal vein to 60 penetrate the latter and split and tear large pieces of coal from the unmined mass.

4. In a mining machine, the combination with a supporting frame, of digging mechanism mounted thereon, and means comprising a pair of alternately operable roof jacks

for moving said frame to effect the operation of said digging mechanism.

5. In an arc-wall mining machine, the combination with a main frame, of a supplemental frame pivoted thereto to swing on an upright axis, dislodging mechanism comprising a series of spaced-apart knife-edged penetrating wedging tools each adapted to penetrate the solid upright face of a mine vein and by wedging action split large pieces of mineral 75 therefrom over a wide area, said dislodging mechanism being rigidly connected to said supplemental frame to move bodily therewith horizontally along the working face from one side of the mine chamber to the other, and 80 means back of said supplemental frame in position to give the latter a powerful pushing action along an arc on said upright axis to effect the operation of said dislodging mechanism along an upright mine wall in its native 85 state in the mine vein.

6. In a mining machine, the combination with a portable frame, of dislodging apparatus mounted thereon to move bodily therewith and comprising digging mechanism rigidly connected thereto, and means comprising walking roof jacks for moving said frame along an upright mine wall to effect the operation of said dislodging apparatus.

7. In a mining machine, the combination with a movable frame, of a supplemental frame pivotally connected thereto for arcuate movement on an upright axis, dislodging apparatus mounted on said supplemental frame to move bodily therewith and comprising 100 mechanism adapted to penetrate deeply the solid face of the mine vein and by wedging action split large pieces of coal therefrom, said coal splitting mechanism being rigidly connected to said supplemental frame in position to project forwardly therefrom in an upright series, and walking-roof jack mechanism for forcibly moving said supplemental frame arcuately relatively to said first-named frame to effect the operation of said dislodging mechanism.

8. In a mining machine, the combination with supporting framework, of coal splitting mechanism comprising spaced-apart splitting tools, a supplemental frame for supporting said splitting tools for bodily movement therewith in position to project from the upper side of said supporting frame to dislodge material approximately in the plane of the roof of the mine chamber at the upper portion of the mine wall, means for rectilinearly adjusting the elevation of said splitting tools to adapt the same to roofs of varying heights from the floor, and means for forcibly moving said supplemental frame continuously forward to cause the splitting mechanism to dig into the material in its native bed straight along the roof and dislodge the material therefrom.

9. In a mining machine, the combination

- with a frame, of coal-splitting mechanism mounted thereon to move bodily therewith, a pair of roof jacks, fluid pressure motors between said roof jacks and said frame, and means for controlling the operation of said roof jacks and of said fluid pressure motors to cause said roof jacks to be moved forward to anchoring positions alternately and to cause said frame to be moved forward step-by-step to force said coal-splitting mechanism into engagement with the coal to split the latter from the unmined mass. 5
10. In a mining machine, the combination with a frame, means for adjusting the elevation of said frame, dislodging mechanism mounted on said frame, a roof jack, a fluid pressure motor connected between said roof jack and said frame and adjustable in elevation along said roof jack, and means for 15 controlling the operation of said dislodging mechanism by effecting movement of said frame by the operation of said fluid pressure motor when said roof jack is in anchored position. 20
11. In a mining machine, the combination with a frame, of coal splitting mechanism mounted on said frame in position to penetrate and by wedging action split coal from an upright mine wall adjacent the roof of the 25 mine chamber, means for vertically adjusting the elevation of said coal splitting mechanism in accordance with the height of the roof, roof-jack mechanism to serve as abutment mechanism, and fluid-pressure motor mechanism between said abutment mechanism and said coal splitting mechanism to push the latter along the coal vein to operate said coal splitting mechanism. 30
12. In a mining machine, the combination with a frame, of a piercing wedging tool pivoted to said frame on a horizontal axis in position to act on the roof of a mine chamber, a fluid pressure motor for adjusting the position of said tool relative to said frame, and 35 hydraulic means for moving said frame pivotally to effect bodily movement therewith of said tool to cause the latter to dislodge material from such roof. 40
13. In a mining machine, the combination with a movable frame, of a digging tool pivoted thereto and projecting downwardly therefrom in position to dig into the coal of a mine vein along the floor of a mine chamber to split portions of the coal from the unmined mass, fluid pressure mechanism for adjusting the position of said digging tool relative to said frame and locking such tool in adjusted position to hold it rigidly connected to said frame for bodily movement 55 therewith, and hydraulic means for exerting powerful pressure on said frame to operate said digging tool in its adjusted position to split coal from the floor of a mine chamber. 60
14. In a mining machine, the combination with a supporting frame, of a supplemental 65 frame mounted thereon to swing arcuately on an upright axis, dislodging mechanism mounted on said supplemental frame, a roof jack, and a fluid pressure motor pivotally connected to said roof jack and pivotally connected to said supplemental frame to move said dislodging mechanism arcuately while said roof jack is anchored. 70
15. In a mining machine, the combination with a movable frame, of dislodging mechanism mounted thereon, a pair of roof jacks, a plurality of fluid pressure motors pivotally connected to said roof jacks and pivotally connected to said frame, and means for controlling the operation of said roof jacks and the operation of said motors to secure a walking action of said roof jack and a step by step forward movement of said frame to effect the operation of said dislodging mechanism. 75
16. In a mining and loading machine, the combination with a frame of dislodging mechanism mounted on said frame for movement along a mine wall in a predetermined direction, said dislodging mechanism comprising a series of spaced-apart penetrating splitting tools, a traveling conveyor on said frame in advance of said dislodging mechanism in position to receive the material as dislodged by said dislodging mechanism, means for moving said frame to cause said splitting tools to penetrate the mineral in its native bed and by wedging action split large pieces therefrom onto said conveyor, and means for operating said conveyor while maintained in fixed relation to said dislodging mechanism for bodily movement therewith. 80
17. In a mining and loading machine, the combination with a main frame, of a supplemental frame connected to said main frame to swing on an upright axis, multiple digging mechanism mounted at the outer end of said supplemental frame to have an arcuate path of travel when said supplemental frame is swung on said upright axis, hydraulic means for swinging said supplemental frame to effect the operation of said digging mechanism to dislodge material along an arcuate upright mine wall, and loading apparatus comprising a conveyor with a receiving end adjacent said dislodging mechanism and in advance thereof. 85
18. In a mining and loading machine, the combination with a main frame, of a supplemental frame swingable on an upright axis, dislodging mechanism mounted on said supplemental frame and dependent entirely upon movement of the latter for its operation, hydraulic mechanism for swinging said supplemental frame to impart to said dislodging mechanism a translating movement corresponding to that of said supplemental frame to thereby effect the operation of said dislodging mechanism, and loading apparatus comprising a conveyor on the front 90

portion of said supplemental frame in position to receive the material as dislodged and convey such material toward loading position.

5 19. In a mining and loading machine, the combination with a movable frame, of a conveyer mounted thereon, a scoop on the front side of said frame in position to direct material from the floor of the mine chamber 10 onto said conveyer, dislodging mechanism rearwardly of said conveyer and in fixed relation thereto in position to dislodge material from an upright mine wall onto said conveyer, and means for bodily moving said 15 dislodging mechanism together with said conveyor to effect dislodgment of material from an upright mine wall onto said conveyer.

20. In a mining and loading machine, the 20 combination with a movable frame, of a conveyer mounted thereon, means in advance of said frame but bodily movable therewith for directing material from the floor of a mine chamber onto said conveyer, dislodging 25 mechanism mounted on the other side of said conveyer in fixed relation thereto for bodily movement therewith while occupying a position to dislodge material so as to be received by said conveyer, and means for 30 exerting continuous pressure on such dislodging mechanism to move the same bodily together with said conveyer and said directing means.

35 21. In a mining and loading machine, the combination with a movable frame, of a traveling conveyer mounted thereon, means for penetrating the coal to split and tear it from the native vein, said penetrating means being mounted on said frame, means for 40 moving said frame to cause said means to thus dislodge the coal from the unmined mass, and reciprocating mechanism for transferring dislodged coal onto the receiving end of said conveyer.

45 22. In a mining and loading machine, the combination with a movable frame, of a conveyor mounted on the front portion thereof, dislodging mechanism mounted on the rear portion of said frame, means for 50 operating said dislodging mechanism to dislodge material from an upright mine wall at the receiving end of said conveyor in front of the dislodging mechanism, and reciprocating mechanism for transferring dislodged material on to said conveyor.

55 23. In a mining and loading machine, the combination with a movable conveyor, of dislodging mechanism following said conveyor in position to dislodge material at the receiving end of said conveyor, and means for moving the dislodged material on to the receiving end of said conveyor while the latter remains in advance of said dislodging mechanism.

60 24. In a mining and loading machine, the

combination with a main frame, of a supplemental frame, an endless conveyor inclined downwardly toward the floor, dislodging mechanism mounted on said supplemental frame rearwardly of the receiving end of 70 said conveyor, means for swinging said supplemental frame on an upright axis on said main frame to effect the operation of said dislodging mechanism while said conveyor remains in fixed relation thereto, and reciprocating mechanism mounted on said supplemental frame in position to transfer dislodged material on to said conveyor. 75

25. In a mining machine, the combination with a main frame, of a supplemental frame 80 swingably mounted thereon, dislodging mechanism mounted on said supplemental frame, means for swinging said supplemental frame to effect the operation of said dislodging mechanism, and a self-contained 85 kerf cutting machine mounted on said main frame to operate independently of said dislodging mechanism including a swinging feeding movement on approximately the upright axis of swinging movement of said supplemental frame.

26. In a mining machine, the combination with a main frame, of a supplemental frame 90 mounted on said main frame to swing relatively thereto on an upright axis, kerf cutting mechanism mounted on said main frame to swing on such upright axis independently 95 of said supplemental frame, digging mechanism mounted on said supplemental frame, means for swinging said supplemental frame 100 on such upright axis to effect the operation of said digging mechanism, and means for operating said kerf cutting mechanism including swinging movement thereof on such upright axis to kerf-cut the mine wall in advance of the operation of said digging operation. 105

27. In a mining and loading machine, the combination with a main frame, of a supplemental frame swingable on an upright axis 110 on said main frame, loading apparatus comprising conveyor mechanism on said main and supplemental frames, digging mechanism on said supplemental frame, means for swinging said supplemental frame to effect 115 the operation of said digging mechanism, kerf cutting mechanism mounted on said main frame to swing on approximately said upright axis independently of the swinging of said supplemental frame, and means for operating said kerf cutting mechanism including swinging feeding movement thereof on such upright axis to effect kerf cutting in 120 advance of said digging mechanism.

28. In coal mining apparatus, the combination with a supporting frame, of a horizontally swinging tool-carrier on said supporting frame, a plurality of spaced-apart dislodging tools each adapted to penetrate 125 the coal in its native vein and by wedging ac- 130

tion split and tear the coal from the unmined mass, and hydraulic means for swinging said tool-carrier horizontally and relatively to said supporting frame to effect the operation of said dislodging tools to dislodge the coal from an upright mine wall over an area extending from the floor to the roof of the mine chamber.

29. In a coal mining apparatus, the combination with a supporting frame, of universally adjustable kerf cutting mechanism mounted thereon, loading apparatus comprising conveyor mechanism on said supporting frame, and means for dislodging the material cut by said kerf-cutting mechanism and delivering such dislodged material to said conveyor mechanism.

30. In a mining machine, the combination with a frame movable laterally along a coal face, dislodging mechanism mounted on said frame, a conveyor extending in operation from points outside the coal face to the base of the mine wall in advance of said dislodging mechanism, a plate arranged to move beneath the dislodged material, reciprocating means for causing said plate to deliver dislodged material to said conveyor, and motor mechanism for operating said dislodging mechanism and said conveyor.

31. In a coal mining and loading apparatus, the combination with a frame, means for causing said frame when moving to follow a curvilinear path, cutting mechanism for forming a horizontal kerf in the coal, digging mechanism for forming vertical cleavage in the coal inside of the front face thereof, and power driven conveyor mechanism mounted on said frame in position to receive the material dislodged by such vertical cleavage.

32. In a coal mining and loading apparatus, the combination with a pivot device adapted to be fastened stationarily to the mine floor, of a radius frame mounted on and swinging around said pivot device, a bottom plate at the outer end of said radius frame, a motor and power mechanism connected to said bottom plate to reciprocate the same relatively to said frame, an endless conveyor mounted on and movable relatively to said frame and having its receiving end in delivery communication with said bottom plate and its delivery end at the aforesaid pivot device, vertical cleavage mechanism on said radius frame arranged to break down the coal on to said plate and the receiving end of said conveyor, and power-actuated devices for moving the said radius frame together with said conveyor and said bottom plate and said cleavage mechanism around said pivot device.

33. In coal mining and loading apparatus, the combination with a main frame, of a radius frame mounted on and swingable around an upright axis on said main frame, penetrating mechanism mounted on the outer end of said radius frame with the space

in advance thereof free and unobstructed, means for operating said penetrating mechanism to penetrate the coal in its native bed and split and tear the coal from the unmined mass along upright cleavages spaced back from the face of the mine wall, and conveyor mechanism mounted on said radius frame with its receiving end on radial lines in front of the radial position of said penetrating mechanism.

34. In coal mining and loading apparatus, the combination with a stationary main frame, of a radius frame mounted to swing on an upright axis on said main frame, of coal digging mechanism free and unobstructed along horizontal lines in front of said digging mechanism, means for swinging said frame to cause said digging mechanism to effect upright cleavage of the coal to dislodge the same, and an endless conveyor mounted on said radial frame in position to receive the dislodged material and transfer same toward said upright axis during the swinging of said frame and the operation of said digging mechanism.

35. In a mining and loading machine, the combination with digging mechanism for effecting upright cleavage of coal from the upright face of an arcuate mine wall, of means for operating said digging mechanism including swinging feeding movement thereof through an arc of 180 degrees or more, a conveyor mounted in fixed relation to said digging mechanism with its receiving end below the horizontal paths of travel of said digging mechanism, and an additional conveyor having a receiving end continually in delivery communication with said first-named conveyor while the delivery end of said additional conveyor is held over a predetermined loading position.

36. In a mining and loading machine, the combination with a supporting frame, of digging mechanism mounted on said supporting frame in position to effect upright cleavage of material along an upright mine wall spaced back from the face thereof, means for operating said digging mechanism to dislodge crescent-shaped masses of material from its native bed, a main conveyor, a swinging supplemental conveyor mounted in fixed relation to said digging mechanism, and means for directing dislodged material from the base of the mine wall on to said supplemental conveyor for movement thereby onto said main conveyor.

37. In a mining and loading machine, the combination with a support, a cleavage mechanism pivotally connected thereto with a free and unobstructed space in advance thereof along horizontal planes, means for operating said cleavage mechanism to dislodge material from an upright mine wall, a main conveyor, a supplemental conveyor pivotally connected to said support and occupying a

position in fixed relation to said cleavage mechanism, and means for directing dislodged material onto said supplemental conveyor for transfer to said main conveyor.

38. In a mining machine, the combination with a movable frame, of a plurality of digging tools arranged in an upright series with a tool intermediate the floor and roof in advance of the other tools in position to dislodge an intermediate section of material from an upright mine wall prior to the dislodging of sections above or below, and hydraulic means for exerting force on said frame to effect the arcuate operation of said digging tools to dislodge intermediate sections in advance of sections above and below such intermediate section.

39. In a mining machine, the combination with a supporting frame, of kerf-cutting mechanism mounted on said frame to have a swinging-feeding movement on an upright axis at the forward portion of said frame, dislodging mechanism mounted on said supporting frame for swinging-feeding movement on said upright axis and comprising a series of spaced-apart penetrating wedging tools for engaging the kerf cut bodies of the mine vein to tear the same asunder from the unmined mass, and power-operated mechanism for forcing said tools along their arcuate dislodging paths of travel on such upright axis.

40. In a mining machine, the combination with kerf-cutting mechanism for cutting a horizontal kerf intermediate the floor and roof of a mine chamber, of a movable frame, digging devices carried by said frame, and power-operated mechanism acting on said frame to cause said digging devices to dislodge from the unmined mass bodies of material above and below such kerf.

41. In a mining machine, the combination with kerf-cutting mechanism for cutting a horizontal kerf intermediate the floor and roof of the mine chamber, of a movable frame, dislodging mechanism carried by said frame in position to penetrate the solid mineral above and below said horizontal kerf, and power-operated mechanism acting on said frame to cause said dislodging mechanism to dislodge the unmined mass of bodies of material from the floor to such kerf and from the roof to such kerf.

42. In a mining machine, the combination with a supporting frame, of kerf-cutting mechanism mounted thereon, a supplemental frame connected to said supporting frame to swing relatively thereto, dislodging mechanism comprising spaced-apart penetrating wedging devices connected to said supplemental frame rigidly to move bodily therewith, said penetrating wedging devices being in position to act on the solid face of the mine vein outside of the kerf cut by said kerf-cutting mechanism, and power-operated mech-

anism acting on said supplemental frame to operate said dislodging mechanism to dislodge said kerf-cut material.

43. In a mining and loading machine, the combination with a main frame, of a supplemental frame mounted on said main frame for swinging movement on an upright axis through an angle of 180 degrees or more, spaced-apart penetrating wedging tools mounted on said supplemental frame in position to pierce the upright face of a solid coal vein and by wedging action split the coal from the unmined mass in large pieces over a wide area, digging mechanism pivoted to said supplemental frame in position to move bodily therewith along the floor of the mine chamber adjacent the base of the mine wall, and hydraulic means for swinging said supplemental frame on such upright axis to effect the operation of the coal splitting mechanism and at the same time effect the operation of said digging mechanism to split masses of material from the floor and thus trim it approximately to the level of the floor in front of the upright mine wall.

44. In a mining machine, the combination with a supporting frame, of kerf cutting mechanism mounted thereon to swing in an arc on an upright axis to cut a horizontal kerf in an upright mine wall, of dislodging mechanism comprising a penetrating wedging tool mounted on said frame to swing along an arc on said upright axis in position to penetrate the solid mineral outside of said kerf to dislodge the material adjacent said kerf, and mechanism for exerting a continuous forward force on said dislodging mechanism without retracting the same to secure the breaking down of the material adjacent said kerf.

45. In a mining machine, the combination with a supporting frame, of a kerf cutter mounted thereon to swing on an upright axis, a digger mounted on said frame to swing in an arc in position to act on the material outside of said kerf to dislodge the same adjacent said kerf, and means for exerting force on said digger to move the same forward only and cause the same to dig into the mine wall and split portions of material from the unmined mass.

46. In a mining machine, the combination with a supporting frame, of kerf-cutting mechanism thereon, digging mechanism mounted on said frame in position to dislodge material adjacent the kerf produced by said kerf-cutting mechanism, digging mechanism mounted on said frame for movement relatively thereto in position to act outside of the cut kerf to dislodge material adjacent said kerf, and means for giving said digging mechanism a slow forward movement with sufficient force to dig into and split portions of the mine wall from the unmined mass.

47. A mining and loading machine comprising apparatus for dislodging a crescent-shaped mass of material from a mine wall, a main conveyer, a supplemental conveyer arranged to be in advance of said dislodging apparatus during movement of the latter along an arc of 180° or more, and means for operating said supplemental conveyer to deliver dislodged material to said main conveyer throughout such range of movement of said supplemental conveyer.

48. In a mining and loading machine, the combination with a main conveyer, of a supplemental conveyer mounted for arcuate movement while remaining in delivery communication with said main conveyer, and digging mechanism mounted behind said supplemental conveyer and adapted to move always forward to split portions of material from an upright arcuate mine wall into position to be received by said supplemental conveyer while the latter remains in advance of said digging mechanism.

49. A mining and loading machine comprising apparatus for digging into an upright mine wall and splitting therefrom a crescent-shaped mass of material in one continuous feeding movement, means for operating said apparatus including arcuate feed thereof, a main conveyer, and a supplemental conveyer communicating with said main conveyer throughout a range of approximately 180° for delivering dislodged material from the mine wall to said main conveyer during the operation of said dislodging apparatus.

50. A mining machine comprising a frame, piercing wedging mechanism stationarily mounted on said frame for operation on a mine wall by concentrated pressures distributed at spaced-apart points along such mine wall, and power-operated mechanism comprising walking roof jacks for moving said frame along the upright mine wall to effect the operation of said piercing wedging mechanism to secure such distributed concentrated pressures to split the coal in large pieces from a mine wall over a wide area.

51. A mining machine comprising a frame, dislodging mechanism stationarily mounted on the frame for operation on an upright mine wall, power-operated mechanism comprising roof jacks, and fluid pressure motors between said roof jacks and said frame for moving the frame along the upright mine wall to effect the operation of the dislodging mechanism.

52. A mining machine comprising a frame, dislodging mechanism stationarily mounted on said frame for operation on an upright mine wall, a pair of roof jacks, fluid pressure motors connected respectively between said roof jacks and said frame, means for controlling the operation of said roof jacks and of said fluid pressure motors to cause said roof jacks to be moved forward to anchoring

positions alternately and to cause the frame to move forward step-by-step to effect the operation of said dislodging mechanism, and means for adjusting the elevation of the dislodging mechanism.

53. A mining machine comprising a frame, dislodging mechanism stationarily mounted thereon for operation on an upright mine wall, power-operated mechanism comprising roof jacks, fluid pressure motors for moving the frame along the upright mine wall to effect the operation of the dislodging mechanism, and means for adjusting the elevation of the fluid pressure motors along the roof jacks.

54. A mining machine comprising a frame, dislodging trimming tools mounted on said frame in stationary position relative thereto while in operation on an upright mine wall, pivotal mountings for said tools in position to act on the roof and floor of the mine chamber, fluid pressure motors serving for adjusting the positions of the dislodging tools relative to said frame, and power-operated mechanism for moving said frame along the upright mine wall to effect the operation of such dislodging mechanism.

55. A mining and loading machine comprising dislodging mechanism, a conveyer disposed in advance of the dislodging mechanism, and means comprising a scoop in advance of the conveyer for directing material from the floor of the mine chamber to the conveyer.

56. A mining machine comprising a plurality of claw-like, straight knife-edged piercing wedging tools disposed in an upright series and distributed over the mine wall between the floor and the roof of the mine chamber, means for supporting a tool intermediate the floor and the roof in advance of the other tools in position to dislodge an intermediate section of the mine vein in large pieces prior to the dislodging of sections above and below, and means for operating said tools by a unidirectional force to move the tools continuously along the mine wall back from the face thereof to effect the splitting of the mineral in large pieces both above and below such tools and the dislodging of such mineral over a wide area of the face of the mine vein and extending from the floor to the roof.

57. The method of mining coal from the solid of a mine vein to dislodge large pieces therefrom, which consists in deeply penetrating and wedging coal to split the same from the unmined mass by the application of forces distributed at spaced-apart positions across the face of the mine vein, trimming the floor and roof by removing ragged projections left after such dislodgment of the coal, and cutting a kerf in the mine vein between the floor and the roof.

58. A mining machine including a frame,

spaced-apart knife-edge piercing wedging tools each mounted on said frame in stationary position relative thereto and each adapted to penetrate the solid face of a mine vein and by wedging action split and tear 5 large pieces of mineral therefrom, means for adjusting said tools relatively to each other and relatively to said frame, and power-operated mechanism for operating said tools 10 while all of them remain stationary relative to said frame.

59. A mining machine including a frame, spaced-apart digging tools each mounted on the frame in stationary position relative thereto for operation on an upright mine wall, and mechanism comprising walking roof jacks for moving the frame along the upright mine wall to effect the operation of the dislodging mechanism.

60. In a mining machine, the combination with a supporting frame, of dislodging mechanism mounted thereon and comprising spaced-apart penetrating wedging tools adapted to split large pieces of coal from a mine vein, walking roof jacks, fluid pressure motors between said roof jacks and said tools, and means for controlling the operation of said roof jacks and of said fluid pressure motors to cause said roof jacks to be moved 25 forward to anchoring positions alternately and to cause said tools to be fed forward step-by-step.

61. In a mining machine, the combination with a supporting frame, of dislodging mechanism mounted thereon, a roof jack, a fluid pressure motor connected to said dislodging mechanism, and a connection between said motor and said roof jack to serve as an abutment when said roof jack is anchored, said connection being slideable up and down on 35 said roof jack.

62. In a mining machine, the combination with a movable frame, of spaced-apart penetrating wedging tools mounted on said frame 45 to move therewith, means for moving said frame arcuately to feed said tools, and a floor jack having an adjustable floor-engaging shoe to guide said frame over the floor during the feed of said tools.

63. In a mining machine, the combination with a supporting frame, of dislodging mechanism mounted thereon, walking roof jacks, fluid pressure motors adjustable in elevation along said roof jacks and connected between the latter and said dislodging mechanism, and means for controlling the operation of said roof jacks and of said fluid pressure motors to cause said roof jacks to be moved forward to anchoring positions alternately and to cause the operation of said dislodging mechanism.

64. In a mining machine, the combination with a supporting frame, of dislodging mechanism mounted thereon in position to operate 65 on an upright mine wall, additional dislodg-

ing tools pivotally mounted on said frame to act on the floor and roof of the mine chamber, fluid pressure motors to adjust the positions of said additional tools, and hydraulic means for operating all of the aforesaid dislodging mechanism and tools to secure operation thereof.

65. In a mining machine, the combination with a supporting frame, of dislodging mechanism mounted thereon and comprising a plurality of knife-edge piercing wedging tools distributed in an upright series for operation on the upright face of a mine vein, a conveyor disposed in advance of said dislodging mechanism for carrying away the material broken down from the mine wall by the said piercing wedging tools, a scoop mounted in advance of the conveyor for directing material from the floor to said conveyor, means for operating said conveyor, and means for operating the dislodging mechanism by causing said tools to penetrate the solid face of the mine vein and by wedging action split and tear the material from the mine vein while said conveyor remains in advance of said dislodging mechanism.

66. In a mining machine, the combination with a supporting frame, of a supplemental frame pivotally connected thereto, dislodging mechanism on said supplemental frame, means for swinging said supplemental frame to feed said dislodging mechanism, self-contained kerf-cutting mechanism mounted on said supporting frame for swinging feeding movement along the mine wall operated on by said dislodging mechanism, means for bringing said kerf-cutting mechanism into co-operation with said dislodging mechanism for keeping it out of operation during the operation of said dislodging mechanism, and means for adjusting the height and inclination of said kerf-cutting mechanism independently of said dislodging mechanism.

67. In a mining machine, the combination with a supporting frame, of a series of spaced-apart knife-edged penetrating wedging tools mounted on said frame one adjacent the floor of the mine chamber and another adjacent the roof of the mine chamber and a third intermediate tool advanced ahead of the floor and roof tools to dislodge an intermediate section of material from the mine wall prior to dislodging adjacent sections, and means for operating the tools to cause the same to penetrate the solid face of the mine vein and by wedging action split large pieces of mineral over a wide area without being accompanied by any more than a very small amount of fine particles of the mineral.

68. In a mining and loading machine, the combination with a main frame adapted to occupy a stationary position, of a main conveyor mounted on said frame in fixed relation thereto, a supplemental frame mounted at the forward end of said main frame for

swinging movement relatively thereto on an upright axis from a position at right angles to the longitudinal length of said main frame at one side thereof to a position at right angles to such longitudinal length at the other side of said main frame, a conveyor on said supplemental frame in delivery communication with the main conveyor throughout an angle of approximately 180°, a rear swinging conveyor mounted to swing laterally through a wide angle relatively to said main frame, means for maintaining delivery communication between said main conveyor and said rear swinging conveyor throughout the range of angular movement of the latter, dislodging mechanism comprising an upright series of penetrating wedging tools mounted on said supplemental frame to move bodily therewith in position to dislodge the material from the upright mine wall to be received by said forward swinging conveyor, and means for swinging said supplemental frame to effect the operation of said dislodging tools and the maintenance of said swinging conveyor in receiving position relative to said dislodging tools.

69. In a mining machine, the combination with a supporting frame, of transporting mechanism therefor comprising traction treads, roof jack mechanism co-operating with said traction treads to anchor said supporting frame, dislodging mechanism comprising an upright series of penetrating wedging tools mounted on said frame to have a swinging-feeding movement relatively thereto on an upright axis, and means for operating said dislodging mechanism including swinging-feeding movement thereof while said main frame remains anchored by said roof jack mechanism and said traction treads.

In testimony whereof I have signed my name to this specification on this 19th day of December, A. D. 1919.

EDMUND C. MORGAN.
